FLUID LEAKAGE INDICATOR

Charles W. Cox, Springfield, Pa., Francis A. Donovan, Wilmington, Del., and John T. Frantz, North Hills, Pa., assignors to American Viscose Corporation, Wilmington, Del., a corporation of Delaware

Application July 19, 1951, Serial No. 237,522

14 Claims. (Cl. 116—114)

1

This invention relates to a fluid leakage indicator and more particularly to a device for determining when oil, which is employed as a lubricant in various machines and equipment for handling aqueous fluids or solutions, leaks into an aqueous fluid which it is desirous and/or necessary to keep free of contamination. Further, the invention relates to a device which, in addition to indicating when oil has leaked into an aqueous treating fluid or the like, also traps the oil up to a predetermined amount and prevents it going into a treating or other system.

Various aqueous treating baths and liquids are employed in many intricate processes throughout the chemical industry. In the majority of these processes, it is of extreme importance that such aqueous treating liquids and solutions be kept free of foreign matter and undesirable fluids in order to obtain a uniform and non-contaminated product. As of necessity, lubricating oil must be employed in the pumps for feeding the liquids and also in the moving parts of the machinery employed in carrying out the various steps of the above-mentioned processes. In such instances, it is necessary to closely guard against the oil finding its way into the treating liquids or chemicals involved in the processes, otherwise the ultimate product will become adulterated. Therefore, there is a need for some simple and easily installable means for quickly and easily observing the infiltration by the lubricating oil into the treating chemical or other fluid or solution so that such infiltration may be corrected before serious damage occurs to the product.

Accordingly, it is an object of the present invention to provide an apparatus or device which will indicate, or which will enable one to detect by visual means, the presence of a non-miscible fluid, such as oil, and the like, when present in a treating fluid or aqueous solution or a mixture of treating fluids of heavier specific gravity.

It is another object of the invention to provide a fluid leakage indicator which is simple in construction, easily and readily installed in existing fluid supply lines and which will also act as a trap for the undesirable fluid within certain pre-described limits.

Other objects and advantages of the present invention will be apparent from the description thereof hereinafter.

While the present invention is applicable to being used in any instance where there is danger of one undesirable and non-miscible liquid commingling with an aqueous fluid or treating liquid of heavier specific gravity, the invention will be

2

described as it applies to the instance where oil contaminates a treating solution or solutions such as those employed in the rayon industry. As is well known, it is extremely important in producing fibers and filaments for making yarns and threads that they be kept free of deleterious materials and particularly lubricating oils used in the fiber and filament producing apparatus. If any of the yarns or filaments are contaminated with oil, fabrics produced therefrom would be unsalable resulting in a great loss even though only a small portion of the yarns or filaments were so contaminated. It is to be understood, however, that this is merely intended for purposes of illustration and the invention is not to be limited thereby but only insofar as the same may be limited by the appended claims.

The objects of the present invention are in general accomplished by inserting in a fluid delivery line or conduit, a device comprising a transparent gage glass cylinder having a top and bottom cover, and a sleeve positioned internally of the cylinder and extending between the covers and having a plurality of slots or openings spaced thereabout on the bottom edge thereof. The bottom cover has an extension projecting upwardly inside the sleeve and also has a downwardly extending portion which is threaded to fit into a pipe, conduit, bracket or the like. The upwardly extending projection or extension has an axial opening or bore therein which opens to the outside of the device and has a plurality of cooperating openings, perpendicular to the axial opening, communicating with the chamber formed by the sleeve, said openings being positioned adjacent the top of the extension or projection. The fluid or treating liquid is admitted to the chamber formed between the gage glass cylinder and sleeve in the top, bottom, or intermediate the top and bottom thereof and leaves by the axial opening in the extension. The oil or other undesirable non-miscible liquid can readily be seen since being of a lighter specific gravity than the treating fluid, it floats on top of the fluid in the outer chamber, i. e., the above mentioned chamber formed between the gage glass cylinder and the sleeve.

In order to more clearly understand the following detailed description of the invention, reference should be had to the accompanying drawing which is merely intended to be illustrative and not limitative, and in which

Fig. 1 is a sectional elevation view of a preferred form of the apparatus; and

55

Fig. 2 is a sectional elevation view of another alternative embodiment of the invention.

Referring to Fig. 1 of the drawing, the device comprises a transparent glass or gage glass cylinder 3 which has a top cover 4 and a bottom cover 5 attached thereto. The glass cylinder 3 fits into the annular grooves 6 and 7 in the covers 4 and 5, respectively, and is fitted against the gaskets 8 and 9 which are fitted into the grooves 6 and 7.

Extending upwardly from the top cover 4 is a projection 9a into which is fitted the flexible conduit 10. This comprises the liquid inlet. If desired, the conduit 10 may be non-flexible, such as a metal or glass pipe, and the like. Extending downwardly from the bottom cover 5 and integrally attached thereto is a threaded projection 11 by means of which the device is fitted into the conduit 12 or any other device or apparatus to which the treating fluid must be directed.

Positioned internally of the glass cylinder 3 is a sleeve 13 which fits over and surrounds the upwardly extending portion of projection 14 of the bottom cover 5. Adjacent the bottom edge of the sleeve 13 are a plurality of openings 15 equally spaced thereabout. The projection or extension 14 has an opening or bore 16 therein coincident with its axis. In the upper portion of the extension 14 there are a plurality of openings 17 spaced thereabout which are perpendicular to and communicate with the opening 16 in the member or extension.

The sleeve 13 fits over the downwardly extending portion or projection 18 on the upper cover 4. The sleeve 13 thus causes the formation of two separate chambers in the device, namely chamber 19, between the sleeve and the glass cylinder 3 and the chamber 20 being the interior of the sleeve 13.

An opening 21 is cut through the top cover 4 of the device to permit the passage of the screw 22 therethrough which extends into the threaded opening 23 in the projection or extension 14. By means of the screw 22, the various parts of the device or apparatus are held together. If desired, however, the various parts may be held together by integrally attaching the sleeve 13 to the projection 16 and the bottom cover 5.

The various parts of the apparatus, exclusive of the glass cylinder, such as the covers 4 and 5 and the sleeve 13, may be made of any suitable material which is resistant to the particular fluid or solution being passed therethrough. Preferably, however, the various parts above mentioned may be molded from any suitable plastic such as saran, copolymers of vinyl acetate and vinyl chloride, urea-formaldehyde, and the like.

Referring to the embodiment shown in Fig. 2, the flexible inlet tubing 10 is fastened to the downwardly extending portion 26 attached to the lower cover 5. It is to be noted that in this instance there is an upwardly extending hollow portion or conduit 27 attached to the bottom cover 5 and communicating with the opening in the extension or projection 26. This is necessary in order to direct the oil which may be mingled with the treating fluid away from the openings 15. This is the only change in the embodiment over that shown in Fig. 1.

In operation, the device, such as shown in Fig. 1, may be inserted anywhere in the fluid line that is convenient. The fluid enters through the projection 9a and, as indicated by the arrows, passes through the openings 15 upwardly through the chamber 20, through the openings 17, and

then down through the opening or axial bore 16 to the place where it is to be employed. Should there be oil or other non-miscible fluids in the treating fluid being conveyed through the apparatus, it will remain in the chamber 19 since, being of lighter specific gravity than the treating fluid and since there is insufficient pressure to carry it down to the openings 15, it will remain on the surface of the treating fluid in the chamber 19. In this way it will be readily visible to one looking through the glass cylinder. Preferably, the lubricating oil employed in the apparatus should be colored by any suitable means for easy detection thereof. This is particularly true when the treating fluid itself may have a slight color.

The present device is advantageous in that it is simple of construction and may readily be inserted in any existing fluid line. The present device also acts as a trap for the oil which has managed to leak into the system and prevents its further passage through the system in contact with the product being produced or being treated.

The size of the device or fluid leakage indicator can vary with the capacity of the fluid line or lines to which it is to be connected or with the visibility of the liquid which is to be passed therethrough. However, although the size may be varied, the essential design, such as shown in the embodiments of the drawing, should not be changed appreciably.

It is to be understood that changes and variations may be made without departing from the spirit and scope of the invention as defined in the appended claims.

We claim:

1. A fluid leakage indicating device comprising a transparent cylinder having a top cover and a bottom cover, a sleeve positioned internally of the cylinder and extending between the covers, a plurality of slots in the bottom edge of the sleeve, a fluid opening communicating with the chamber formed between the cylinder and sleeve, a projection extending upwardly from the bottom cover into the sleeve, and a fluid outlet passage in the projection.

2. A fluid leakage indicating device comprising a transparent cylinder having a top cover and a bottom cover, a sleeve positioned internally of the cylinder and extending between the covers, a plurality of slots in the bottom edge of the sleeve, a fluid inlet opening communicating with the chamber formed between the cylinder and sleeve, a projection integrally attached to the bottom cover and extending upwardly therefrom into the sleeve, a fluid outlet passage in the projection, and an opening in the projection adjacent the top thereof and communicating with the passage.

3. A fluid leakage indicating device as defined in claim 2 wherein there are means for fastening the top cover to the projection.

4. A fluid leakage indicating device comprising a transparent cylinder having a top cover and a bottom cover, a sleeve positioned internally of the cylinder and extending between the covers, a plurality of slots in the bottom edge of the sleeve, a fluid inlet opening in the top cover communicating with the chamber formed between the cylinder and sleeve, a projection integrally attached to the bottom cover and extending upwardly therefrom into the sleeve, a fluid outlet passage in the projection, and an opening in

the projection adjacent the top thereof and communicating with the passage.

5. A fluid leakage indicating device as defined in claim 4 wherein there are means for fastening the top cover to the projection.

6. A fluid leakage indicating device as defined in claim 5 wherein the means for fastening the top cover to the projection comprises a threaded bore in the top of the projection and a screw passing through the top cover and fastened in the bore.

7. A fluid leakage indicating device comprising a transparent cylinder having a plastic top cover and a plastic bottom cover, a sleeve positioned internally of the cylinder and extending between the covers, a plurality of slots in the bottom edge of the sleeve, a fluid inlet opening in the top cover communicating with the chamber formed between the cylinder and sleeve, a projection integrally attached to the bottom cover and extending upwardly therefrom into the sleeve, a fluid outlet passage in the projection comprising an axial bore, and a plurality of openings in the projection adjacent the top thereof, said openings being perpendicular to and communicating with the axial bore.

8. A fluid leakage indicating device as defined in claim 7 wherein there are means for fastening the top cover to the projection.

9. A fluid leakage indicating device as defined in claim 8 wherein the means for fastening the top cover to the projection comprises a threaded bore in the top of the projection and a screw passing through the top cover and fastened in the threaded bore.

10. A fluid leakage indicating device comprising a transparent cylinder having a top cover and a bottom cover, a downwardly extending portion integrally attached to the top cover and positioned centrally thereof, a sleeve positioned internally of the cylinder and extending between the covers, said sleeve fitting over the said downwardly extending portion of the top cover, a plurality of slots in the bottom edge of the sleeve, a fluid opening communicating with the chamber formed between the cylinder and sleeve, a projection integrally attached to the bottom cover and extending upwardly therefrom into the sleeve, a fluid outlet passage in the projection comprising an axial bore, a plurality of openings in the projection adjacent the top thereof, said openings being perpendicular to and communicating with the axial bore.

6
municating with the axial bore, and means for fastening the top cover to the projection.

5 11. A fluid leakage indicating device as defined in claim 10 wherein the means for fastening the top cover to the projection comprises a threaded bore in the top of the projection and a screw passing through the top cover and fastened in the threaded bore.

10 12. A fluid leakage indicating device as defined in claim 11 wherein the opening communicating with the chamber is a fluid inlet opening in the top cover.

15 13. A fluid leakage indicating device comprising a transparent cylinder having a top cover and a bottom cover, a downwardly extending portion integrally attached to the top cover and positioned centrally thereof, a sleeve positioned internally of the cylinder and extending between the covers, said sleeve fitting over the said downwardly extending portion of the top cover, a plurality of slots in the bottom edge of the sleeve, conduit means attached to the bottom cover and extending upwardly into the chamber formed between the cylinder and sleeve, a fluid inlet opening in the bottom cover communicating with the conduit means, a projection integrally attached to the bottom cover and extending upwardly therefrom into the sleeve, a fluid outlet passage in the projection comprising an axial bore, a plurality of openings in the projection adjacent the top thereof, said openings being perpendicular to and communicating with the axial bore, and means for fastening the top cover to the projection.

20 25 30 35 14. A fluid leakage indicating device as defined in claim 13 wherein the means for fastening the top cover to the projection comprises a threaded bore in the top of the projection and a screw passing through the top cover and fastened in the threaded bore.
